211,720

ROCKER SEAT FOR A CHILD OR SIMILAR ARTICLE

Jack M. Lue, 549 Ladera St.,
Monterey Park, Calif. 93940

Filed Aug. 25, 1967, Ser. No. 8,388

Term of patent 14 years

(Cl. D15—6)

FIG. 1.

FIG. 2.

FIG. 5.

FIG. 3.

FIG. 4.

FIGURE 1 is a plan view of a rocker seat for a child, showing my new design.

FIGURE 2 is a side elevational view of one of the two identical sides.

FIGURE 3 is a front elevational view thereof.

FIGURE 4 is a rear elevational view thereof.

FIGURE 5 is a section taken along line 5—5 of FIGURE 1.

I claim:

The ornamental design for a rocker seat for a child or similar article, substantially as shown and described.
